MASS SPECTROMETER FOR ANALYSING SUBSTANCES OR INDICATING A SMALL AMOUNT OF A DETERMINED SUBSTANCE

Nicolaas Warmoltz, Eindhoven, Netherlands, assignor to Hartford National Bank and Trust Company, Hartford, Conn., as trustee

Application April 23, 1953, Serial No. 350,577

Claims priority, application Netherlands May 6, 1952

8 Claims. (Cl. 250—41.9)

This invention relates to mass spectrometers for analysing substances or indicating a small amount of a determined substance.

It is known that mass spectrometers are very suitable for separating particles of different molecular weight. In this case the molecules of a gas are ionised, whereby, as a rule, separation occurs, whereafter the ions are subjected, for example, to the combined action of an electric field and a magnetic field. In the electric field the ions acquire a certain velocity and in the magnetic field they are deflected from their path and this more strongly, according as the mass of the ions is smaller and their load is higher. As a rule, said types of mass spectrometer is constituted by a semicircular tube, of which one extremity contains an ionisation device and the other extremity contains the members required for separating the ions according to the mass. Said members are constituted inter alia by a screen comprising a narrow slit, behind which a collector is arranged. In most mass spectrometers of known type, the collector is connected to an amplifier, of which the output circuit acts upon an indicator instrument, for example, a meter or an oscilloscope.

The invention relates more particularly to the device for indicating the ions after being separated according to the mass, and has for its purpose to increase its sensitivity in such manner that it is also possible to indicate a constituent of a gas-mixture having an extremely small partial pressure.

The invention consists in that provision is made of an electrostatic system which is so arranged with respect to the collector that the electrons released therefrom by the ions are accelerated and led to a Geiger-Müller counter or a scintillation counter which is connected to an indicator system.

In this case it is preferable that the collector which, as a rule, is plate-shaped and which has a positive voltage relatively to the surroundings should be arranged in a somewhat inclined position in such manner that the mean direction of movement of the emerging electrons does not coincide with the path of the ions striking the collector. The sensitivity may be further increased either by manufacturing the collector from material having a high capacity of emitting secondary electrons or coating the collector with such material.

The electrons emerging from the collector having a comparatively low velocity and are accelerated by means of a plurality of perforated electrodes of positive potential, so that the velocity increases up to some tens of kilovolts, which suffices to cause the electrons to pass through the gate or window of the Geiger-Müller counter. Many millions of electron volts would be required to cause the ions themselves to enter the Geiger-Müller counter.

Since the velocity of the electrons emerging from the collector is so small, the electrons may readily be focused with the use of a magnetic field in such manner that a still larger portion of the electrons is used for the actuation of the Geiger-Müller counter. According to a further

feature of the invention, for this purpose a magnetic field is produced in the vicinity of the collector, which field is so directed that a large proportion of the emerging electrons, after traversing the accelerating electric field, strikes the window of the Geiger-Müller counter.

In order that the invention may be readily carried into effect, it will now be described with reference to the accompanying drawing showing, by way of example, two embodiments thereof.

The figures only show that portion of the mass spectrograph which is essential to the invention. The ionisation device and the part in which the ions are separated are thus omitted.

In Fig. 1, reference numeral 1 indicates a beam of ions of the constituent of a gas being analysed. As a rule, the beam is band-shaped having its largest dimension at right angles to the plane of drawing and passes through a narrow slit provided in a screen 2, which may be followed by a second screen 3, which likewise comprises a slit, the latter screen being given a potential such that the ions in the space between the two screens are subject to a certain acceleration. The ions finally impinge upon the collector 4, losing thereon their charge. For this purpose the collector is connected to a point having a potential substantially equal to that of the electrode 3.

When the ions impinge upon the collector 4, they release therefrom electrons 10, which have a comparatively low speed of emergence, viz. of the order of a few volts. In order to increase the number of emerging electrons, the collector 4 may either consist of material having a high capacity of emitting secondary electrons, for example beryllium, or it may be coated with such material.

According to the invention, provision is made of a plurality of apertured electrodes 5, 6 and 7, which have positive potentials, preferably progressing, such that the released electrons are sufficiently accelerated, so that their velocity, after having passed the last electrode 7, has become such that the electrons can penetrate the window of a Geiger-Müller counter 8. Said window may be constituted by a mica plate of some thousandths of a millimeter thick, as is known per se. The discharges brought about in the Geiger-Müller counter by the incoming electrons are counted by means of a device 9. They may be counted individually, but it is also possible to measure the mean electron current. A comparatively small amount of ions striking the collector per unit-time already provides an indication which is clearly perceptible, so that the described device permits of obtaining a high sensitivity in the sense that it is possible to indicate a very small concentration of a determined gas.

The assembly, except the device 9, may be arranged in the glass envelope or earthed metal envelope 11 for the tube of the mass spectrometer. If the envelope is of metal, the electrode 2 is preferably connected to the envelope in a conductive manner. The electrode 3 may have a negative potential of about 15 kilovolts relatively to earth. The potential of the electrode 7 may be 15 kilovolts positive or higher relatively to the collector 4.

Fig. 2 shows a modification of the device for counting secondary electrons. Here the electrons emerging from the collector 4 are subject to the action of a magnetic field and an electric field, of which the lines of force are at right angles to one another. The electrons emerge from the collector in different directions, the spatial division of the velocity approximately following a cosine regularity, such as shown in Fig. 3. The magnetic lines of force are at right angles to the plane of the drawing so as to be substantially parallel to the surface of collector 4. The electric field is produced by the electrodes 4, 12 and 14. The electrons emerging at different angles traverse cycloidal paths 15 between the electrodes 12 and 14, it being possible by suitable choice of the strength of

the magnetic field and of the potentials of the electrodes 12 and 14 that the greater portion of the electrons or at least a very large portion is focused at the window of the Geiger-Müller counter 8. The electrode 12 is apertured at this area. The electrons may be further accelerated by means of an electrode 13, which may have a positive potential of a few kilovolts relatively to the surroundings. 16 designates a screening cap for electrode 13, which is connected in an electrically conductive manner to the electrode 12.

As a rule, the electrode 14 will have a positive potential of some hundreds of volts with respect to electrode 12. The collector 4 may be connected in a conductive manner to the electrode 12. Each of said electrodes preferably has a negative potential which is approximately equal to that of the electrode 3, for example from 10 to 15 kilovolts.

Similarly as in the device shown in Fig. 1, the various electrodes and the counter 8 are arranged in the envelope for the tube of the spectrometer, which envelope is not shown here. As an alternative, the Geiger-Müller counter may be arranged under the plate 12 at the area at which the electron paths closely approach one another.

The devices described are very suitable as leak detectors, that is to say for finding leaks in vacuum tubes. In this case the interior of the tube under investigation is connected to the interior of the spectrometer tube. The tube under examination is surrounded by a determined gas which may be indicated by means of the mass spectrometer, even in extremely small concentration, if there is a leak in the tube.

The Geiger-Müller counter may be substituted by a crystal counter which is constituted by a crystal which becomes fluorescent or conducting under the action of electrons and a device for measuring small amounts of light, for example, a photo-sensitive member with amplification or a counter of current pulses.

What is claimed is:

1. In a mass spectrometer having means producing a beam of ions, a collector in the path of said beam adapted to produce electrons when struck by said beam, electrostatic accelerating means disposed in the vicinity of said collector for accelerating said electrons, radiation detecting and counting means responsive to incident electrons for detecting the same and disposed to receive said accelerated electrons, and indicating means coupled to said detecting means.

2. In a spectrometer as claimed in claim 1 wherein the detecting means is a Geiger-Müller counter.

3. In a spectrometer as claimed in claim 1 wherein the detecting means includes a scintillation counter.

4. In a spectrometer as claimed in claim 1 wherein the collector is mounted in an inclined position with respect to the path of the beam, said collector inclining toward said electrostatic accelerating means.

5. In a spectrometer as claimed in claim 1 wherein at least the surface of the collector facing said ion-producing means consists of a material exhibiting good secondary-electron-emitting properties.

6. In a mass spectrometer having means producing a beam of ions, a collector in the path of said beam adapted to produce electrons when struck thereby, electrostatic accelerating means including at least one perforated plate maintained at a positive potential disposed in the vicinity of said collector outside of the path of the ion beam for accelerating and directing said electrons, a Geiger-Müller counter positioned to receive said accelerated electrons and produce electrical signals corresponding in intensity to that of the electrons, and indicating means coupled to said counter.

7. In a mass spectrometer as claimed in claim 6 wherein means are provided producing a magnetic field in the vicinity of said collector for focussing the electrons onto the counter.

8. In a mass spectrometer as claimed in claim 7 wherein the magnetic lines of force are substantially at right angles to the electrostatic lines whereby the electrons describe a cycloidal path before being detected by the counter.
